FIG. 1.

FIG. 2.

Inventor:
Russell E. Vanderhoff,
By: Cox x Moor atty

UNITED STATES PATENT OFFICE

91,255

DESIGN FOR A PLATFORM SCALE CASING

Russell E. Vanderhoff, Chicago, Ill., assignor to
Health-O-Meter Company, Chicago, Ill., a cor-
poration of Illinois

Application October 25, 1933. Serial No. 49,549

Term of patent 14 years

To all whom it may concern:

Be it known that I, RUSSELL E. VANDERHOFF, a citizen of the United States, residing at Chicago, Cook County, Illinois, have invented a new, original, and ornamental Design for a Platform Scale Casing, of which the following is a specification, reference being had to the accompanying drawing, forming part thereof, showing my design.

Figure 1 is a perspective view of the article showing my new design; and

Figure 2 is a side elevation of the article.

I claim:

The ornamental design for a platform scale casing as shown.

RUSSELL E. VANDERHOFF.
